(57) **CLAIM**

The ornamental design for a side gusseted flexible beverage container, as shown and described.

DESCRIPTION

FIG. 1 is a forward perspective view of my design of a side gusseted flexible beverage pouch illustrating the characteristic features of the design which resides in its shape together with having an opaque upper portion and transparent middle portion, and opaque lower portion on both the front and back of the pouch;

FIG. 2 is a front elevational view thereof, the rear view being identical;

FIG. 3 is a left side elevational view thereof, the right side elevational view being identical;

FIG. 4 is a top view thereof; and,

FIG. 5 is a bottom view thereof.
